UNITED STATES PATENT OFFICE.

WILLIAM BUSOLD, OF WEST ORANGE, NEW JERSEY, ASSIGNOR TO THE TRIMBLE HAT COMPANY, OF ORANGE, NEW JERSEY, A CORPORATION OF NEW JERSEY.

HAT WELT AND PROCESS OF FORMING SAME.

Application filed August 10, 1927. Serial No. 211,906.

My invention relates to a method of finishing the brims of felt hats, or hats of like materials, and to the novel welt-like edge obtainable thereby. It has for its objects to 5 form the edge of the hat brim of a hat of felt, wool or hair, or of similar materials, with a novel and superior finish consisting of a welt-like edge that will be sufficiently supple to permit particular shaping of the brim, and 10 that will retain the curves imparted to it by the maker and the wearer; that will simulate a welt and perform all the useful functions of a welt; and that will be usable either alone or in conjunction with a welt; and that, when 15 used as substitute for a welt, will cost much less in labor and materials than the welt edge.

I attain the foregoing objects and others hereinafter more particularly set forth by the hereinafter described process which will be 20 better understood by reference to the accompanying drawings in which Figure 1 is a side view of a soft hat whose brim shows the finished edge embodying my invention; Figure 2 is a plan view of a portion of the brim 25 shown in Figure 1, and Figure 3 is a view of said brim in vertical section. Figure 4 is a view similar to Figure 3, showing the edge produced when my process is applied to supplement the usual welt, the brim in this figure 30 having an overturned welt. Figure 5 is a corresponding view of a brim having an undeturned or reverse welt. Figure 6 is a side view in elevation of a tool or shackle adapted for use in the practice of my process and 35 Figure 7 is a view of the bottom of said tool.

Like reference numerals indicate the same or like parts throughout these several figures, in which 1 is the body of a hat of felt or the like material and 2 is the brim. In Figures 40 1, 2 and 3 is shown a brim having the so-called "raw edge" 3. 4 is a groove in the upper side of this brim and 5 is a groove in the under side thereof. 6 is a welt on the brim, formed by overturning the edge upon the 45 brim and stitching thereto. 7 is a reverse welt, the brim edge being turned back upon the underside of the brim and stitched therethrough. 8 is a tool adapted to produce the 50 grooves adjacent the brim edge by compressing the fibres of the felt, 9 being the under surface of the tool adapted to contact with the brim, 10 a recessed portion, 11 the groove-forming edge, and 12 the bevel thereof; 13 being the supports for the handle 14.

55 In weling felt hats it is the practice to turn the brim edge back upon itself with a curling iron, in the usual manner in which a welt is formed, and to secure the over-turned edge by stitching with the usual welt-stitching machine. As is understood by hat makers, if 60 the edge is turned back on the upper side of the brim, the machine-stitching may be all the way through or only partially through, so as not to show on the under side; but if the edge is turned back against the under side 65 of the brim to form what is termed a "reverse welt", the stitching cannot be "blind" but must be all the way through the welt. This welt serves to finish the raw edge and to reinforce it so that the brim, when shaped by 70 bending, will retain the set given it.

In practicing my invention as applied to a welted brim, the welt may be formed in either of these ways, and thereafter my invention is preferably practiced as follows: the brim 75 edge is damped and a depression is formed, by rolling or ironing, in the side opposite that on which the welt is over-lapped, adjacent the inner edge of the welt. This depression is formed by crushing the wet felt with a hot 80 iron, preferably by a shackle having an edge adapted to roll the felt into a groove. The heat of the iron will cause rapid evaporation of the moisture, and the felt will thus be shrunk to hold the groove impressed in it. 85 This groove gives the appearance of a blind-stitched welt, and produces the effect of a double welt both in appearance and in the reenforcement of the brim by stiffening the edge.

In lieu of forming a welt, as described, my 90 invention particularly contemplates the attainment of the advantages of a welt both as to finish and brim-reinforcement, while dispensing entirely therewith. To this end, I 95 form a groove adjacent the raw edge of the brim, upon one side therof and a second groove, upon the opposite side, parallel to the first but slightly offset therefrom. Preferably I form the groove in the upper side of the brim about one quarter of an inch from the edge, and the groove in the lower side about one half of an inch from the edge. These two grooves afford such a thickening 100 of the felt in the two depressed parts that the brim is stiffened adequately to retain its shape while permitting flexibility for bending to suit the individual taste and style of the wearer and to keep the set thus given it.

As is obvious, when the double grooves are used in a raw edge brim, all the steps of welt- 110

ing as now practiced may be dispensed with and the cost of labor in curling and stitching is saved.

By my process I produce the appearance of a double welt, blind stitched on both sides, with all the advantages of a single welt and at approximately a quarter of the cost.

I believe this substitute for the welt and the method of forming either the double or single groove to be broadly new in hat-making, and therefore claim:

1. A felt hat having a brim, a welt around the edge of said brim, and a permanent groove in the side of the brim opposite the welt, the

grooved portion of the brim being shrunk 15 and having greater rigidity than the remaining portion of the brim, the welt side of the brim being smooth from the welt to the crown.

2. A felt hat having a brim and a zone of shrunk compressed felt in said brim, adjacent 20 the edge of the brim only, the felt in said zone being more compact than the felt in the other parts of said brim, and forming a permanent groove adjacent to the edge of the brim, both surfaces of the brim being smooth between 25 said groove and crown.

WILLIAM BUSOLD.
